METHOD AND APPARATUS FOR FORMING
RAISED CHARACTERS AND LINES

Harry P. Sewell, Forest Hills, N. Y.

Application June 23, 1949, Serial No. 100,938

13 Claims. (Cl. 41—1)

1

This invention relates to a method and apparatus for manually forming raised lines on the upper surface of a sheet of material, enabling the blind to read. Heretofore, symbols for the blind have been made on the underside of a sheet by pressing a hand tool into the sheet, necessitating the sheet to be turned over before it could be read by the blind. Under this invention line drawings are adapted to be made on the upper surface of a sheet enabling a blind person to distinguish the drawing or message as he progresses without having to turn the sheet each time between the formation and reading.

One object is to provide a method and apparatus for forming a raised line on the upper or impression-receiving surface of a sheet to be read without having to turn the sheet over. Another object is to enable a drawing or handwriting message to be made without recourse to Braille. Still another object is to form a line or lines as a message legible to both the blind and persons with sight. Yet a further object is to enable a sighted or blind person to write or draw quickly and easily for the benefit of another blind person, without the limitations of the Braille system.

Specifically this is accomplished by means of a stylus stretching local portions of a sheet of material enough to give such portions a permanent set and substantially simultaneously with said stretching raising the stretched portions above the plane of the sheet. The formation of a line is preferably effected by means of a ball point stylus moving along regenerated cellulose sheeting known as cellophane. Pressure on the cellulose sheet presses it into a smooth resilient gum rubber sheet about one sixteenth inch thick, stretching the cellulose sheet both laterally and longitudinally under the stylus giving it a permanent set and causing the stretched area to be raised as the stylus moves along the sheet when the rubber is mounted on a non-yielding foundation.

Referring to the drawing,

Fig. 1 is a top plan view of a preferred type pad upon which lines or characters are to be formed.

Fig. 2 is a section on the line 2—2 of Fig. 1.

Fig. 3 is a longitudinal section of the lower end of the stylus or ball point pen used in forming a raised line.

Fig. 4 is an enlarged detail partly in section showing a type of raised line capable of being made under this invention.

Fig. 5 is a top plan view of a portion of the sheet.

2

The pad for receiving the lines and symbols under the present invention comprises a stiff back 10 of any appropriate material, wood, metal or fiberboard. On the back 10 is secured a sheet 11 of smooth gum rubber one-sixteenth of an inch thick. As shown in Fig. 2 of the drawing, the rubber layer 11 may be secured by means of cement or other appropriate securing means illustrated. Over the rubber and on which the lines are drawn is a sheet of a tough grade of regenerated cellulose 12 known as cellophane and having a thickness of .0016 inch. Bolts 13 and rivets 14 secure spring fingers 15 in place to hold the cellulose sheet 12 on the rubber pad during writing or drawing. Knurled nuts 16 on the bolts 13 control the tension or pressure of the fingers on the sheet 12 so that by loosening these nuts the sheet 12 may be slid out and another sheet replaced.

In Fig. 3 is shown the lower part of a preferred stylus 17 constituted by a ball pointed pen. The ball 18 preferably has a diameter of .045 inch. In the reservoir 19 may be carried the usual ink or if no ink is used and the writing is entirely for the blind a lubricating oil is maintained. Between the ball and the reservoir 19 is a passage 20, .02 inch in diameter, to prevent either the lubricant or the ink from flowing too freely. This stylus is used for forming lines in writing or drawing.

Unlike prior practise in making lines or symbols, the present invention permits the formation of such lines or symbols on the top surface of the sheet rather than on the under side as heretofore has been the practise with drawing devices and a Braille slate. This new method obviates the need to turn over the drawing to be read, and which has in the past always appeared in a reverse position.

To operate the stylus 17 in the formation of raised lines on the right side of the sheet 12, such tool is held at preferably a small angle to the vertical, such as 5° to 10° although the stylus may be held at an angle to the vertical of as much as 30°. Using only light pressure, a fairly light raised line will be formed. However, by using slightly heavier pressure than is used in drawing, it will be possible to form a heavier raised line, and the heavier raised line 29 as shown in Fig. 5 will be characterized by gathered portions 30 at frequent uniform intervals. The resulting interrupted line is more easily comprehended by the feeling finger of a blind reader as it is passed along the line.

The exact nature of what transpires when the cellulose sheet 12 is operated upon by the stylus 17

is not understood with certainty. However, it is believed that the stylus effects a permanent stretching of the cellulose both transversely and longitudinally of the line being formed. Perhaps it is not the reaction from the live rubber alone which forces the stretched portions of the cellulose upward since motion of the stylus is needed to effect the raised line. It is therefore believed that movement of the ball creates a wave in both the rubber and cellulose layer which has the effect of longitudinally stretching portions of the cellulose in the raised line. Possibly it is the reaction of the pressure wave in the yieldable sheets 11 and 12 which assist in the production of the permanently stretched raised line. At least, the stretch seems certain. The degree of pressure and degree of longitudinal stretch are believed responsible for the gathered portions. Too thin a cellophane sheet is likely to be torn by the pressure of the stylus, whereas if the sheet is too thick, the raised line may not be as clear, and too thick a sheet 12 detracts from definition in the finished product. The resilient sheet 11 needs to be considerably thicker than the sheet 12 in which the markings occur. If the rubber 11 is too thick, the cellophane may be torn and if it is too thin, more than a convenient degree of pressure or power is needed.

Other materials than cellophane have been found appropriate, for example, the usual fibrous paper used for receiving Braille characteristics, will be appropriate, and a cellulose acetate sheet has also been found satisfactory. The chief characteristic of such a sheet 12 is that it must be capable of being stretched readily by the stylus to receive a permanent set by the stretching, yet not be resilient because the resilience would cause the sheet to return to its former position without having any raised portion. Also, other materials than rubber will be found appropriate, the needed characteristic being appropriate resilience to the sheet 11.

With the present stylus one blind person is enabled to write or draw quickly and easily for the ready interpretation by another blind person of what has been written or drawn, since the writing is on the right or upper side of the sheet 12, and it is not necessary for the sheet to be turned over to be read. This invention opens up a new field to the blind. It enables maps and drawings to be made so as to be quickly sensed by either the seeing or the blind. Whenever writing or drawing is intended for both the seeing and the blind, the raised lines will be made when the stylus is filled with ink instead of a lubricant. A stylus of a different type than that illustrated is also appropriate, for example, an ordinary pencil, if the point is not too sharp, might suffice for the formation of the necessary structure and raised lines. The ball point pen is preferred because it rolls and its point is always of a given shape that does not change. A comparatively large diameter ball 13 is preferred to reduce the danger of the paper being torn during the writing or drawing, and the ink or oil lubricates the ball so as to make certain that it will be free to roll, thereby minimizing any tendency to pull and undesirably deform the cellophane.

Due to the width of the raised lines formed by the stylus of Figs. 3 and 4, there is substantially little, if any, danger of a cellophane sheet of the thickness mentioned being punctured or torn.

An important advantage of this invention resides in its ready adaptability for use in executing drawings in duplicate. The method and ap-

paratus remain substantially unchanged. It is simply necessary for either the sighted or blind operator to use two superimposed sheets of cellophane instead of the aforesaid single sheet. By following the same technique previously described, the under sheet will simultaneously produce raised lines corresponding to those being inscribed on the upper sheet. Thus, a reference copy of a drawing may be obtained, which has been quite impossible with any other line drawing system heretofore known.

A new field is now opened for producing raised line tracings of ink drawings, charts, graphs, maps, symbols, electrical circuits, etc. Here again, the aforesaid technique is used, but with a slight modification of the apparatus. The sheet 11 made of a latex which possesses a degree of transparency, is substituted for the non-transparent sheet 11, and the ink drawing intended to be traced in raised line form, is placed under the transparent sheet 11. Then a cellophane sheet 12 is positioned on top of the rubber sheet 11, and the tracing is executed by a sighted person in the previously described manner without damaging the original ink drawing, since it is shielded from direct contact with the stylus by the intermediate sheet 11. Traced raised line copies may be similarly obtained directly from ink print papers, books, periodicals, etc. without the aid of a skilled person, and likewise without damaging the originals which may often be costly, such as valuable books.

I claim:

1. A process of forming a raised line which comprises stretching a tough substantially inelastic and stretchable sheet of material to give it a permanent set in tension along and across a narrow elongated area under pressure of a moving stylus having a point shaped to avoid tearing said sheet 35 pressing said sheet into a resilient sheet thicker than the inelastic sheet and without tearing such inelastic sheet as the stylus is moved along the impression receiving side of said first sheet, and then raising said stretched portion above the plane of said first mentioned sheet under the impetus of rebound of said second sheet upon removal of pressure of said stylus as it is moved along said sheet.

2. A process according to claim 1 in which the 50 rebound of said second sheet is assisted by its being compressed against a substantially non-yielding foundation.

3. A process according to claim 2 in which said first sheet has a stretch and toughness equivalent 55 to that of a sheet of regenerated cellulose known as cellophane .0016 inch thick, and the second sheet has an elasticity equivalent to that of a gum rubber .06 inch thick.

4. A process according to claim 3 in which the narrow stretched area is substantially as wide as that formed in using a ball point pen in which the ball has a diameter of .045 inch.

5. A process according to claim 1 in which the pressure on said stylus is heavy enough to produce laterally gathered portions or dots along a line.

6. A process according to claim 1 in which said stylus is held at an angle of 0° to 30° to the vertical during most of the formation of said raised line.

7. A process according to claim 1 in which said stylus is a ball point pen and a substantial part of the stretched area of said first sheet is coated with ink.

8. A process according to claim 1 in which said

stylus is a ball point pen having no ink therein but in which the ball is supplied with a lubricant.

9. A process of forming a raised line which comprises stretching a narrow elongated area of a sheet of material having the stretch and toughness of regenerated cellulose known as cellophane .0016 inch thick under pressure of a moving ball point stylus pressing the material into a second sheet of material having the resilience substantially equivalent to that possessed by a sheet of gum rubber .06 inch thick, and raising the stretched area of said first sheet above the plane thereof under the impetus of the release of pressure from said second sheet and its live rebound when said second sheet has been compressed between a non-yielding foundation and said stylus pressing and stretching said first sheet.

10. A process of simultaneously forming raised lines on sheets of tough cellophane which comprises placing said sheets one on the other and on a resilient sheet thicker than said first mentioned sheets, stretching said first sheets simultaneously to give them a permanent set along a narrow elongated area under pressure of a moving stylus having a rounded point, pressing said first sheets into the resilient sheet, and then raising said stretched portions of each of said first sheets above its plane surface under the impetus of rebound of said resilient sheet upon removal of pressure of said stylus as it is moved along said first sheets.

11. A process of forming a raised line tracing which comprises placing a transparent and resilient latex sheet over the sheet to be traced and with a tough cellophane sheet over the latex sheet, stretching the cellophane to give it a permanent set along a narrow elongated area under pressure of a moving stylus having a rounded point pressing said cellophane into said sheet of resilient latex, and then raising said stretched portion above the plane of the upper surface of said cellophane sheet under the impetus of rebound of said latex sheet upon removal of pressure of said stylus as it is moved along over said sheets.

12. Apparatus for forming a raised line on a tough sheet of material which comprises in combination said tough sheet of material being non-elastic and capable of being stretched along a narrow elongated area, a stylus having a point

which is rounded for stretching said material without tearing it under pressure applied to said stylus, a resilient sheet contiguous to said non-elastic sheet and into which said tough material is adapted to be pressed without tearing by said stylus as it is moved over the tough and resilient sheets, said resilient sheet being capable of raising the stretched narrow area of said tough material above the plane of the unstretched portion thereof under the impetus of rebound of said resilient sheet upon removal of pressure of said stylus upon said material and resilient sheet as the stylus is moved along said sheets.

13. A process of forming raised lines upon the top or impression-receiving side of a tough inelastic, stretchable sheet thick enough not to tear under pressure of a stylus having a rounded point upon said inelastic sheet when said sheet is contiguous to an elastic sheet at least several times thicker than the inelastic sheet which comprises moving said stylus along said inelastic sheet, thereby pressing the inelastic sheet into the elastic sheet without tearing it under pressure of said stylus, stretching the inelastic sheet by said stylus longitudinally and transversely of a line being drawn giving such local portions of the inelastic sheet a permanent set in tension and raising said stretched portions of the inelastic sheet above the plane of the rest of said sheet as and after the stylus passes over the sheet probably by a reaction of the elastic sheet.
